UNITED STATES PATENT OFFICE

WILLIAM BOUDINOT CONNER, OF NEW YORK, N. Y.

ADJUSTABLY EXTENSIBLE SHOE FORM

Application filed January 17, 1930. Serial No. 421,512.

This invention relates to an adjustably extensible shoe form adapted to be placed in a shoe when the shoe is not in use or when displayed as merchandise to keep the shoe in proper stretched condition so as to prevent wrinkling of the leather and maintain the shape of the shoe.

A general object of the invention is to provide an extensible shoe form having separate fore and heel parts with provision for a pivotal movement of the heel part upon the fore part for convenience of inserting the form into and withdrawing it from the shoe and also having means whereby all adjustments for the required degree of extension of the form can be conveniently, quickly and accurately made while the form is within the shoe and thus avoid the necessity of trial adjustments of the form outside the shoe with the often attendant objectionable results, from inaccurate adjustments, of either insufficient pressure exerted by the form in the shoe or of undue stretching and distortion of the shoe when the form is forced thereinto.

Another general object of the invention is to embody the provision for pivotal movement of the heel part on the fore part of the form and the means for adjustably extending the form in one structural connection between the fore and heel parts, thus substantially simplifying the form.

Another object of the invention is to make the single structural connection last referred to one of substantial rigidity and one which will positively hold the parts of the form to their extended positions without possibility of their retraction or turning movement out of proper alignment with one another under the reaction pressure of the shoe on the extended form.

Still another object of the invention is to provide a shoe form having the foregoing advantageous features and in which the adjusting means is such as to give a double extension and retraction by simultaneous opposite directions of positive movements of the parts of the form for rapidity as well as accuracy of adjustment.

The foregoing and other objects and the principles of my invention will more fully

appear from the detailed description of a preferred embodiment of the invention herein-after presented and illustrated in the accompanying drawings forming a part of this specification. It is to be understood, however, that the embodiment described and shown in the drawings is simply one example illustrative of the principles of the invention and is not to be taken as limiting the invention to that precise form, the invention including modifications of the embodiment shown and other embodiments according to the scope of the appended claims.

In the drawings:

Figure 1 presents a side elevational view of the adjustably extensible shoe form constituting, as stated above, a preferred embodiment of the invention, with certain interior parts which are not exposed to view shown in dotted lines, and with a showing also in dotted lines, of the heel part of the form pivoted upwardly, the full lines showing the fore and heel parts in that horizontal aligned position they would occupy when in use in the shoe;

Figure 2 presents a bottom plan view of the form with the fore and heel parts in their horizontal aligned position as shown in the full lines in Fig. 1, and with the form in substantially its condition of extension adjustment shown in Fig. 1;

Figure 3 presents a vertical sectional view along the longitudinal axis of the form with certain parts of the operating mechanism shown in elevation and with the extension adjustment substantially as in the other views.

The principles of the invention are such as to enable a simple structure of fore and heel parts to be used without complications of structure or substantial additions thereto for the pivotal connection between the parts or the mounting of the adjusting mechanism. In the present example the fore and heel parts of the simple character referred to are shown at 10 and 11, respectively. They are preferably, although not necessarily, of shell-like or hollow form as shown.

In the illustrative example of the invention, the means effecting the extension and retraction of the form comprises a rotatable

shaft 12 lying in the vertical longitudinal median plan of the form and having screw threaded end portions designed for threaded relation with the fore and heel parts of the 5 form through suitable bosses or mountings on those parts so that the shaft with the bosses or mountings referred to form a rigid straight-line connection and abutment between the fore and heel parts of the form, 10 and a turning of the shaft in opposite directions of rotation extends and retracts the form in simultaneous opposite directions of positive movements of both parts of the form.

15 The mounting for the shaft 12 on the heel part of the form is conveniently provided for by a boss 13 with a threaded bore to receive and cooperate with one of the screw-threaded end portions of the shaft as shown 20 in Fig. 3. The mounting for the shaft 12 on the fore part of the form, in the example shown, comprises a member, of right angular or L-shape in vertical cross section, having a horizontal bottom portion 14 and an 25 upwardly and vertically extending reduced or lug portion 15, as the position of the parts appear in Fig. 3, pivotally mounted on the fore part of the form, and with this lug portion apertured and threaded to receive there- 30 through the adjacent screw threaded end portion of the shaft. For this pivotal mounting, notched lugs 16 are formed on the opposed interior side walls of the fore part of the form to receive and hold, by the pins 17, 35 and thereby to subtend between them, a pintle 18 which extends through a bored boss 19 formed on the upper extremity of the lug portion 15 of the L-shaped member.

40 One of the advantageous features contemplated by the present invention, in association with the provision of a pivotal connection between the fore and heel parts of the form, is the mounting of the operating means for the screw shaft or other extension 45 adjusting mechanism between the fore and heel parts of the form so as to avoid complications of the structure of those parts of the form or of the pivotal member employed in the connection between them either to mount 50 or cooperate with said operating means. In the present example, such operating means comprises a bevel gear 20 fixedly mounted on the unthreaded portion of the shaft 12 and a bevel gear 21 coaxing with the gear 20 55 to drive the same, the gear 21 in turn being manually operated by the handle 22 extending upwardly between the fore and heel parts of the form in convenient position for the manual operation even when the form is 60 in the shoe.

65 Another advantageous feature contemplated by my invention, in association with the pivotal connection between the fore and heel parts of the form, and preferably as a structural part of the pivotal connection, is

the provision of means to keep the fore and heel parts of the form in their proper aligned body positions without any tendency to bodily turn or pivot from those positions in any position of extension adjustment of the 70 form. Where a screw shaft extension connection is used between the fore and heel parts of the form as in the illustrative embodiment of the invention, this means serves to prevent the bodily turning of those parts 75 upon the shaft or with respect to each other.

In the example shown, the means for keeping the fore and heel parts from turning on the screw shaft takes the form of a housing 80 over and fixedly centered by the gear mechanism for operating the screw shaft and with side portions of the housing on opposite sides of the shaft extending into sliding engagement with wall portions of the heel part and the member pivotally mounting the screw 85 shaft on the fore part of the form. The housing referred to, as shown in the drawings, has a top portion 23, two side portions 24 and opposite cross walls 25. The housing may be of any material offering sufficient rigidity 90 combined with lightness, such as thin sheet steel or aluminum, or, if desired, of bakelite or the like synthetic resin composition.

In the present example of the invention, the housing functions to prevent turning 95 movement of the fore and heel parts of the form on the screw shaft by the bottom edges of the side portions 24 pressing on the floor portion 26 of the heel part 11 and on the floor portion 14 of the L-shaped member which 100 is pivotally mounted on the fore part 10 of the form, as shown in Fig. 3. While if desired, the side walls of the housing may also have a close sliding fit with the interior side 105 walls of the heel part of the form, this is not essential to the prevention of turning movement of the heel part of the form on the screw shaft. All the control necessary for both parts of the form may be attained by the contact referred to above of the bottom edges 110 of the housing with the floor portions of the heel part and of the member pivoted to the fore part, and this arrangement has the advantage of permitting such conformation of the fore and heel parts of the form as may 115 present a considerable space between the housing and the inside walls of those parts.

The cross walls 25 of the housing are apertured for the shaft 12, and the top 23 of the housing is apertured for the gear handle 22, the housing thus being centered on the gear mechanism and supported bearing on the shaft 12 and on the bottom portion 26 of the heel part and portion 14 of the member pivoted to the fore part of the form with which portions 14 and 26 the housing has 120 sliding engagement. It is further to be noted from the arrangement of the housing and gears in Fig. 3, that the front cross wall 125 of the housing is positioned on the smooth 123

- unthreaded portion of the shaft 12 and close up against the hub of the small gear 20, and this together with the engagement of the gears 20 and 21 and the journalling of the handle 22 of the gear 21 through the center aperture of the housing effectively centers the housing in fixed position over the shaft and gears between the fore and heel parts of the form.
- 5 To provide a mounting support for the gear 21 and its handle 22 in the top of the housing, that top is provided with a bearing shoulder 27 about the aperture through which the handle 22 extends, and that handle is provided with a shoulder 28 engaging the bearing shoulder 27 for the support of the handle. The gear 21 is then supported from the handle 22, the lower portion or stem of the handle being squared to engage 15 the gear through a similarly shaped aperture therethrough and the stem of the handle being headed over as shown at 29 in Fig. 3. Where aluminum is used for the housing, a brass bearing collar may advisably take the 20 place of the bearing shoulder 27 referred to above.
- The inward movement of the fore and heel parts in the retraction of the form may be limited by the adjacent ends of the L-shaped 25 member pivoted to the fore part and the heel part abutting each other. As a simple and convenient means of limiting the extension movement and preventing the running of the fore and heel parts off the screw shaft, one 30 end of that shaft, the end extending through the pivoted member into the hollow of the fore part of the form, is headed over as indicated at 30 to form a stop for engagement with the adjacent end of the lug 15 to re- 35 strain further turning movement of the screw shaft. With this stop, together with the bottom edges of the housing engaging the fore and heel portions 14 and 26, the parts of the form are locked from further extension 40 movement despite the absence of a stop on the end of the screw shaft which projects into the heel part.
- A heel ring, indicated at 31 on the drawings, is preferably provided for the assistance 45 it gives to the removal of the form from the shoe and for convenience of general handling of the form.
- What is claimed is:
1. An extensible shoe form comprising, in combination, separate fore and heel parts, a member pivotally connected to one of said parts, and adjustable rigid means directly connected to said member and the other part of said form and operable to impart movement to both said fore and heel parts in directions extending and retracting said form.
  2. An extensible shoe form comprising, in combination, separate fore and heel parts, a member pivotally mounted on one of said parts, means forming a structurally rigid connection between said member and the other part of said form, said means being directly connected to said member and the other part of said form and operable to adjust the length of said connection to extend and retract said form in simultaneous opposite directions of movement of both parts of said form in the line of said connection.
  3. An extensible shoe form comprising, in combination, separate fore and heel parts, a member pivotally mounted on one of said parts, means forming a structurally rigid straight-line connection between said member and the other part of said form and operable to adjust the length of said connection to extend and retract said form in simultaneous opposite directions of movement of both parts of said form in the line of said connection, and a structurally rigid element fixedly mounted on said connection between the parts of said form and having sliding engagement with said member and the other part of said form to prevent turning movement of said parts of said form relative to each other.
  4. An extensible shoe form comprising, in combination, separate fore and heel parts, pivotal connection means between said parts enabling said parts to be disposed in aligned relation for use in the shoe and said heel part to be pivoted upwardly for removal of said form from the shoe, said means including a member having a pivotal connection with one of said parts of said form and a shaft in direct threaded engagement with said member and with the other of said parts of said form, and means for turning said shaft whereby both parts of said form may be adjusted along said shaft.
  5. An extensible shoe form comprising, in combination, separate fore and heel parts, a member pivotally connected to one of said parts, and a shaft in direct screw threaded engagement with said member and the other part of said form to turn on said member and said other part in extending and retracting the form, and means for turning said shaft to extend and retract said form.
  6. An extensible shoe form comprising, in combination, separate fore and heel parts, screw shaft means for adjustably extending and retracting said form by simultaneous opposite directions of movement of said parts, a pivotal mounting for said screw shaft means on one of the parts of said form, and a rigid mounting for said screw shaft means in the other of said parts of said form, said pivotal mounting and said screw shaft means forming a connection between said fore and heel parts of said form.
  7. An extensible shoe form comprising in combination, separate fore and heel parts, a member pivotally connected with one of said parts, means forming a connection between said member and the other part of

- said form and having a turning relation with respect to said parts to adjustably extend and retract said form, and means mounted on said connection and engaging 5 said member and said other part of said form to restrain the parts of said form from turning movement relative to each other.
8. An extensible shoe form comprising, in combination, separate fore and heel parts, 10 a member pivotally connected with one of said parts, means forming a rigid connection between said member and the other part of said form and having a turning relation with said member and the other part of said 15 form to adjustably extend and retract both parts of said form, and means fixedly mounted between the parts of said form and slidably engaging said member and said other 20 part of said form to restrain the parts of said form from turning movement on said connection element.
9. An extensible shoe form comprising, in combination, separate fore and heel parts, 25 a member pivotally mounted on one of said parts, a shaft in screw-threaded relation with said member and the other part of said form whereby the turning of said shaft extends and retracts said form, gear mechanism for turning said shaft mounted wholly 30 between said fore and heel parts, a housing fixedly mounted on said gear mechanism, said housing, said pivotally mounted member and said other part of said form being cooperatively formed and arranged 35 for sliding engagement of portions of said housing with portions of said member and said other part of said form in a manner to prevent turning movements of the parts of said form on said shaft.
- 40 10. An extensible shoe form comprising, in combination, separate fore and heel parts, a screw shaft for adjustably extending said form, a mounting for said screw shaft having pivotal connection with one of the parts 45 of said form on opposite sides of the axis of said shaft, and structurally rigid means fixedly mounted over said screw shaft and having sliding engagement with said mounting for said screw shaft on opposite sides of 50 the axis of said shaft.
11. An extensible shoe form comprising, in combination, separate fore and heel parts of shell-like conformation, a member pivotally mounted on one of said parts within 55 the boundary walls thereof, a shaft in direct threaded engagement with said member and with the other part of said form to turn on said member and said other part in extending and retracting the form, and means 60 for turning said shaft.
12. An extensible shoe form comprising, in combination, separate fore and heel parts of shell-like conformation, a member pivotally mounted on one of said parts within 65 the boundary walls thereof, a shaft having 70 threaded relation with said member and with the other part of said form, gear mechanism on said shaft between the parts of said form for turning said shaft, and a housing for and fixedly mounted on said gear mechanism extending between the parts of said form and with sliding engagement with said pivotally mounted member and said other part of the form.
13. An extensible shoe form comprising, 75 in combination, separate fore and heel parts, a shaft in direct screw threaded engagement with said heel part and rigidly extending therefrom, a member pivotally mounting the other end of said shaft on the 80 fore part of said form and permitting turning movement of said shaft on said member, and means for turning said shaft.
